(57) **CLAIM**

The ornamental design for a clip device, as shown and described herein.

DESCRIPTION

FIG. 1 is a top, front, left side perspective view of a clip device according to an embodiment of the present invention.

FIG. 2 is a top plan view of the clip device shown in FIG. 1. FIG. 3 is a right side elevation view of the clip device shown in FIG. 1.

FIG. 4 is a front elevation view of the clip device shown in FIG. 1; and,

FIG. 5 is a rear elevation view of the clip device shown in FIG. 1.

A bottom plan view is not shown; the bottom plan view is identical to the top plan view depicted in FIG. 2.

A left side elevation view is not shown; the left side elevation view is a mirror image of the right side elevation view depicted in FIG. 3.
